(57) **CLAIM**

The ornamental design for a monitoring camera, as shown and described.

DESCRIPTION

FIG. 1 is a top, front, right perspective view of a monitoring camera in accordance with our design;

FIG. 2 is a top plan view thereof;

FIG. 3 is a right side elevational view thereof;

FIG. 4 is a left side elevational view thereof;

FIG. 5 is a front elevational view thereof;

FIG. 6 is a rear elevational view thereof; and,

FIG. 7 is a bottom view thereof.

The broken lines depict portions of a monitoring camera in which the design is embodied and form no part of the claimed design.

1 Claim, 4 Drawing Sheets
